US0D1023664S

(12) **United States Design Patent** (10) **Patent No.:** **US D1,023,664 S**
(45) **Date of Patent:** **** Apr. 23, 2024**

(54) **FOOD PROCESSOR**

(71) Applicant: **Shuangma Plastic Manufacturing Inc.**
Zhejiang (CN)

(72) Inventors: **Xiaoming Wu**, Zhejiang (CN); **Jiali Peng**, Zhejiang (CN)

(**) Term: **15 Years**

(21) Appl. No.: **29/818,083**

(22) Filed: **Dec. 7, 2021**

(51) **LOC (14) Cl.** **31-00**

(52) **U.S. Cl.** USPC **D7/384; D7/372**

(57) **CLAIM**

The ornamental design for a food processor, as shown and described.

DESCRIPTION

FIG. 1 is a front elevational view of a food processor showing our new design;

FIG. 2 is a rear elevational view thereof;

FIG. 3 is a left side view thereof;

FIG. 4 is a right side view thereof; and,

FIG. 5 is a perspective view thereof.

The broken lines illustrate portions of the food processor that do not form part of the claimed design.

1 Claim, 5 Drawing Sheets
